DESIGN FOR A COMBINED VALVE SEAT AND OVERFLOW CONNECTION

Wilbert H. Patten, Trenton, N. J.

Application January 4, 1945, Serial No. 117,252

Term of patent 14 years

(Cl. D91—1)

To all whom it may concern:

Be it known that I, Wilbert H. Patten, a citizen of the United States, residing at Trenton, in the county of Mercer and State of New Jersey, have invented a new, original, and ornamental Design for a Combined Valve Seat and Overflow Connection, of which the following is a specification, reference being had to the accompanying figures of the drawing, forming a part thereof.

Fig. 1 is a perspective view of a combined valve seat and overflow connection showing my new design.

Fig. 2 is a top plan view of the article illustrated in Fig. 1.

Fig. 3 is an end elevation of the article illustrated in Fig. 1.

Fig. 4 is a vertical sectional view of the article illustrated in Fig. 1.

I claim:

The ornamental design for a combined valve seat and overflow connection, substantially as shown.

WILBERT H. PATTEN.
